Atty.

UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

SHUTTLE CHECK FOR LOOMS.

Application filed October 24, 1925. Serial No. 64,556.

This invention relates to a device employed in looms for checking the movement of the picker stick and consequently of the shuttle when the shuttle is boxed and also for checking the movement of the picker stick at the conclusion of its picking movement. The invention relates to that type of mechanism employing a check strap or loop member.

10 The object of the invention is to provide means for retarding the movement of the check strap or loop in accordance with the requirements of the existing conditions.

The object of the invention is further to provide a friction retarding means for the check strap or loop in which the amount of friction may be adjusted or varied as required, in which the friction is applied by yielding pressure and in which the limit of 20 the yielding pressure thus applied is adjustable.

The object of the invention is further to provide a friction retarding means for the check strap or loop which shall be simple in 25 construction, certain in action, and adjustable in its effects.

These and other objects and features of the invention will appear more fully from the accompanying description and drawings 30 and will be particularly pointed out in the claims.

Since the present invention is concerned entirely with the means for checking the movement of the picker stick and of the shuttle and since this mechanism is applicable to a wide range of loom constructions and since the general construction and operation of a loom is well-known and familiar to those skilled in the art, it is only necessary 40 here to illustrate and describe so much of an ordinary type of loom as is necessary to a disclosure of the present invention.

In the drawings:

Fig. 1 is a front elevation of the end portion of a lay and shuttle box, together with the upper portion of a picker stick, together with a preferred form of the present invention.

Fig. 2 is a top plan view partially in horizontal cross section of the check strap and loop and the mechanism for retarding the movement thereof.

Fig. 3 is a view chiefly in vertical cross

section of a detail taken on the line 3—3 of Fig. 2.

Fig. 4 is a view in vertical cross section taken on the line 4—4 of Fig. 2.

In the construction illustrated, the lay 1 supports the shuttle box 2 into which the shuttle, not shown, enters at the end of its flight and from which it is picked by the picker stick 3. This picker stick swings back and forth longitudinally of the lay in the usual manner. The present invention has to do with the retarding or checking of the movement of the picker stick at each end of its throw and consequently of the shuttle when the shuttle enters the box.

The check strap or loop herein shown as a strap of leather 4 is mounted beneath the lay surrounding the path of the picker stick. This strap has its ends 5 clamped by means of a bolt 6 between a plate 7 and a bracket 8 which depends from the lay. The ends 9 of the plate are rounded off and serve as stops for the extreme movement of the strap. The strap thus forms a loop extending horizontally beneath and parallel with the lay and the length of this loop is materially less than the movement of the picker stick, so that as the picker stick nears either end of its throw, it engages an end of the loop of the strap and moves the strap longitudinally.

In this invention the movement of the picker stick is retarded by applying friction to the flexible strap and thus retarding its longitudinal movement.

In the construction illustrated, a bracket 10 is provided having a bed plate 11 adapted to extend beneath and fit against the bottom of the lay and having a flange 12 extending upwardly from the bed plate 11 and fitting against the front of the lay. This bracket is securely bolted in place by bolts 13.

The bracket carries, or has formed integral therewith, a depending vertical bar 14 presenting a rounded face frictionally engaging the inner face of the strap. This bar at its lower end is preferably provided with a forwardly projected foot 15 to prevent downward movement of the strap when loose or when being adjusted.

A base 16 is mounted on the bracket 10 and is adjustable laterally of the strap. For this purpose the bracket 10 is provided with a forwardly projecting slotted flange 17

provided on its bottom face with a guide-way 18 fitting a corresponding guide on the base 16. A bolt 19 passing through the slot in the flange 17 and through a slot in the base 16 enables the base to be adjusted laterally and locked in adjusted position.

The base 16 is provided with a rigid bar 20 depending therefrom and presenting a rounded rear face frictionally engaging the outer face of the strap at one side, at the left, as shown in the drawing, of the bar 14.

The base 16 has also journalled thereon a third bar 21 presenting a rounded face frictionally engaging the outer face of the strap 15 at the other side or at the right of the bar 14 and this bar 21 is yieldingly pressed against the strap.

In the construction illustrated, a vertical stud 22 has its upper end 23 riveted or otherwise firmly secured in the base 16. Beneath the base this stud is provided with a polygonal flange 24 and at its lower end the stud is threaded to receive a nut 25. A sleeve 26, flanged at its upper end 27, is provided also at its upper end with a polygonal recess fitting the flange 24 of the stud. It will thus be seen that if the sleeve 26 is lowered on the stud 22, it may be released from the polygonal flange 24, rotated to any extent desired, and then locked in place by raising it again into engagement with the polygonal flange 24. A horizontally extending tension arm 28, carrying at its free end the bar 21, is provided with a hub 29 journalled on the sleeve 26. The nut 25 with an interposed washer 30 holds the sleeve 26 in position and forms the lower support for the tension arm. A helical spring 31 is coiled about the hub 29 and is connected at its upper end 32 to the flange 27 of the sleeve 26 and at its lower end 33 to the tension arm 28. This spring thus acts to swing the tension arm inwardly and cause it yieldingly to press against the strap. The extent of this pressure is adjusted by rotarily adjusting the sleeve 26 by the means already described. The extent or the limit of movement of the yieldingly pressed bar 21 toward the strap is adjustable. For that purpose a set screw 34 is threaded through a flange 35 projecting upwardly from the tension arm 28 and abuts against the bar 20. This construction also constitutes a further means for adjusting the yielding pressure of the bar 21 against the strap because any adjustment of the set screw 34 alters to some extent the angular relation of the arm 28 and the fixed end 32 of the spring 31.

The head of the screw 34 is so positioned as to receive readily a key or wrench by which the screw may be turned to effect these adjustments while the loom is in operation and without stopping or interfering with its operation.

It will thus be seen that a very wide range

of adjustment of frictional control of the longitudinal movement of the strap 40 is provided. The strap passes in a sinuous course between the three bars, the bar 14 being located at one face and the bars 20 and 21 at the opposite face. The bars 20 and 21, carried by the face 16, are bodily adjustable transversely of the strap relatively to the bar 14, thereby varying the sinuosity of the course of the strap and the retardation action effected by the bars. Furthermore, the pressure of the bar 21 against the face of the strap is a yielding pressure which thus varies according to the conditions and this yielding pressure is itself adjustable primarily by the rotary adjustment of the sleeve 26 and secondarily by the adjustment of the set screw 34. Furthermore, the limit of the pressing movement of the bar 21 is adjustable by means of the set screw 34. It is thus possible very accurately to regulate the retardation of the longitudinal movement of the strap in checking the movement of the picker stick and shuttle so as to meet any required condition.

Having thus described the invention, what is claimed as new, and desired to be secured by Letters Patent, is:

1. A shuttle check for a loom comprising a flexible strap movable longitudinally by the picker stick, three parallel bars separated longitudinally of the strap, one at one face of the strap and two at the other face frictionally engaging the strap and between which and by which alone the strap is caused to pass in a sinuous course, and means for yieldingly pressing one of said bars against the strap, thereby to vary the retardation of the movement of the strap caused by the bars.

2. A shuttle check for a loom comprising the construction defined in claim 1, together with means for adjusting the amount of pressure exerted by said yieldingly pressed bar.

3. A shuttle check for a loom having the construction defined in claim 1, together with means for adjustably limiting the movement of said yieldingly pressed bar toward the strap.

4. A shuttle check for looms comprising a longitudinally movable strap, a stud, a sleeve on the stud, means for rotarily adjusting the sleeve and for locking it in adjusted position, a tension arm journalled on the sleeve and engaging the strap to retard the movement thereof, and a helical spring concentric with the sleeve and secured at one end to the sleeve and at the other end to the arm.

5. A shuttle check for looms comprising a longitudinally movable strap, a stud, a polygonal flange on the stud, a sleeve having a polygonal recess fitting said flange and movable longitudinally and rotarily on the stud, whereby it may be rotarily adjusted on the

- stud and locked in any adjusted position, a tension arm journalled on the sleeve and engaging the strap to retard the movement thereof, and a helical spring concentric with the sleeve and secured at one end to the sleeve and at the other end to the arm.
6. A shuttle check for a loom comprising a flexible strap movable longitudinally by the picker stick, a bracket and means for rigidly mounting it adjacent the strap, a base and means for adjustably securing it to the bracket laterally of the strap, a bar on the bracket frictionally engaging one face of the strap, a bar on the base frictionally engaging the other face of the strap at one side of the first bar, an arm journalled on the base on an axis parallel with said bars and carrying at its free end a third parallel bar frictionally engaging the same face of the strap as the second bar but at the opposite side of the first bar, and means for yieldingly swinging the arm on its axis to press the third bar against the strap.
7. A shuttle check for a loom comprising a flexible strap movable longitudinally by the picker stick, three parallel bars, one at one face of the strap and two at the other face, frictionally engaging the strap and between which the strap passes in a sinuous course, means for yieldingly pressing one of said bars against the strap, thereby to vary the retardation of the movement of the strap caused by the bars, and means operable while the loom is in motion for adjustably limiting the movement of said yieldingly pressed bar toward the strap and for adjusting the yielding pressure of said bar.
- In testimony whereof, I have signed my name to this specification.

HARRY A. DAVIS.
